(74) Attorney, Agent, or Firm — Daniel M. Cohn; Howard M. Cohn

(57) **CLAIM**

The ornamental design for a bookshelf, as shown and described.

DESCRIPTION

FIG. 1 is a top, front, right side perspective view of a bookshelf, showing my new design;

FIG. 2 is a top, rear, left side perspective view thereof;

FIG. 3 is a front elevational view thereof;

FIG. 4 is a rear elevational view thereof;

FIG. 5 is a left side view, the right side view being a mirror image of FIG. 5;

FIG. 6 is a top plan view thereof;

FIG. 7 is a partial enlarged view of FIG. 1; and,

FIG. 8 is a partial enlarged view of FIG. 2.

The broken lines in the figures are for the purposes of illustrating portions of the bookshelf, which form no part of the claimed design.

The dash-dot-dash lines are for an notating enlarged views, which form no part of the claim design.

1 Claim, 8 Drawing Sheets
